Specification for Design.

Patented July 22, 1919.

Application filed May 16, 1919. Serial No. 297,708. Term of patent 3½ years.

To all whom it may concern:

Be it known that I, WILLIAM TURTON, a subject of the King of Great Britain, residing at East Orange, county of Essex, and State of New Jersey, have invented a new, original, and ornamental Design for Members for Bag-Frames, Purse-Frames, and Similar Articles, of which the following is a specification, reference being had to the accompanying drawing, forming part thereof.

Fig. 2 is an edge view of the new and ornamental member for bag frames, purse frames and similar articles.

I claim:

The ornamental design for a member for bag frames, purse frames, and similar articles, as shown.

WILLIAM TURTON.
